RACING PLATE AND METHOD OF MAKING
THE SAME

Carl J. Nardon, Los Angeles, Calif.

Application May 13, 1946, Serial No. 669,385

8 Claims. (Cl. 59—36)

1

This invention relates to horse shoes and particularly pertains to a racing plate and a method of making the same.

It is common practice to equip racing horses with shoes of very light weight known as racing plates. These racing plates have been made of light weight metals or alloys, such as aluminum, for example. The objection to a plate made of this type of material is that the calks wear rapidly. It is necessary, therefore, to attach calks to the plate which are made of hard and strong metal. Heretofore, these calks have been attached by having a portion inserted into the toe and heel sections of the racing plate. These have been objectionable in some instances due to the fact that they may work loose or become separated from the main body of the plate. It is desirable, therefore, to provide a racing plate which is made of light-weight material and to which toe and heel calks may be attached in a manner to insure that they will not become readily separated from the main body of the racing plate under any normal circumstance.

It is the principal object of the present invention, therefore, to provide a racing plate and a method of making the same which will insure that the weight of the plate will be reduced to a minimum and that the toe and heel calks, therefore, will be attached in a manner to give the shoe maximum strength and wear and at the same time allow the shoe to be readily adapted to the contour of the foot of the horse, said shoe being formed by a simple and inexpensive method of manufacture.

The present invention contemplates the production of a racing plate from bar stock material in a simple coining operation and whereby hard metal calks may be permanently associated with said coined racing plate in a manner to impress the body of the plate without impairing its strength.

The invention is illustrated by way of example in the accompanying drawings, in which:

Figure 1 is a view in perspective showing a finished racing plate of the type and construction with which the present invention is concerned.

Fig. 2 is a view in perspective showing the bar stock material after it has been given its initial bend to conform to the shape of a conventional horse-shoe and after its ends have been upset to form a base for the heel calks.

Fig. 3 is a view in perspective showing the toe calk shell.

Figure 3a is a side elevational view of a toe calk cover or shell, a line of bend being indicated in dotted lines.

2

Fig. 4 is a view in perspective showing the details of the heel calk shell.

Fig. 5 is an enlarged view in perspective showing a fragmentary portion of the bar stock as indicated in Fig. 2.

Fig. 6 is an enlarged view in perspective showing the upset end of the heel of the racing plate and with the heel calk shell disposed in its initial position.

10 Fig. 7 is an enlarged view in transverse section taken through the structure as shown in Fig. 5, but indicating it as in reverse position and within a forming die where it is set in its initial position around bar stock material and is clinched into place.

15 Fig. 8 is an enlarged view in transverse section through the coining die and indicates the final operation of placing the toe calk shell upon the bar stock and in coining the bar stock to produce the finished racing plate.

20 Fig. 9 is an enlarged view in transverse section showing the final die operation for the heel calk shell.

25 Fig. 10 is a fragmentary view in elevation showing the bottom face of the finished racing plate and the shell applied thereto.

30 Fig. 11 is an enlarged fragmentary view showing the top face of the toe of the racing plate and indicating the manner in which the shell conforms thereto.

35 Fig. 12 is an enlarged view in elevation showing the fragmentary portion of the racing shoe and indicating particularly the heel calk shell in its final position as viewed from its bottom face.

40 Fig. 13 is a view similar to Fig. 12 showing the opposite edge of a fragmentary portion of the shoe and the manner in which the heel calk shell is clinched into position.

45 Referring more particularly to the drawing, Fig. 2 indicates a length of round stock material which is shown in Fig. 2 of the drawing as being bent in the form of a horse-shoe. This round stock material is ductile in character and of light weight, such, for example, as aluminum. The round stock material is upset at its ends as indicated at 50 Fig. 2 to produce the foundation structure of heel calks. It is intended that the blank racing plate, as generally indicated in Fig. 2, shall be fitted with a toe calk shell 12 and heel calk shells 13 after which the entire shoe is pressed into final shape in a direct coining action. The toe calk shell is struck from a flat blank 14, as indicated in Fig. 3a. This blank is made of any desired 55 grade of steel which is of a selected gauge and as shown in Fig. 3a it comprises a relatively large

field 15 defined on one side by an edge 16 and bound on its opposite side by the dotted line 17. Slightly inclined edge faces 18 and 19 extend along the opposite edges of the field 15. Upon the opposite side of the dotted line 17 is a field 20 which is defined by an outer curved edge 21 interrupted by a V-shaped notch 22 intermediate the length of the edge. The opposite edges of the field 20 are tapered as indicated at 23 and 24. Notches 24' occur at the juncture of the edges 18 and 23 and edges 19 and 24 of the two fields 15 and 20. The blank 14 is then acted upon in a forming die to produce the toe calk shell as indicated in detail in Fig. 3 of the drawings. Here it will be seen that the blank has been folded upon itself substantially along the dotted line 17 and the material has been pressed together so that the field 15 forms the front wall or face of the toe calk and the field 20 forms the back wall. For a distance upon opposite sides of the folding line 17 the front and back fields 15 and 20 are shaped to form a relatively narrow V-shaped groove and a calk blade 25 which is arcuate when considered longitudinally and which has opposite side walls disposed in a slightly divergent angular relation to each other at the edge of the blade portion 25 which occurs intermediate the width of the front field 15. This field is bent upwardly as indicated at 26 and then at an angle to the front face of the calk blade 25 as indicated at 27. At the rear inner edge of the blade 25, as indicated by the line 28 the inner field bends outwardly at an appreciable angle to the surface of the blade to form the portion 29. This terminates in a down-turned annular flange 30 which is interrupted midway its length by the notch 22. The shell 12 thus formed is clinched around the blank 10 in the manner shown in Figs. 5 and 7 of the drawings.

It will be seen by reference to Fig. 7 that a lower die 31 is provided having a cavity defining a V-shaped trough 32 at its bottom and continuing in upper arcuate faces 33 and 34 to engage the fields 15 and 20 and to bend them around the cylindrical surface of the blank 10 and along an arcuate length thereof. A complementary folding die 35 is formed with a die cavity 36 which is substantially semi-circular in cross-section and arcuate in length. This acts to clinch the free edges of the front and back fields of the blank 14 around the back face of the shoe blank 10. The toe calk shell 12 will then assume the position on the bar stock blank 10 as shown in Fig. 5 of the drawings.

The heel calks 13 are then placed in their preliminary positions over the lugs 11. As shown in Fig. 4 the heel calk shells comprise a center hollow structure 37 which is formed in a set of extrusion dies and at the opposite sides of which tangs 38 occur. The heel calk shell 13 is then applied to the calk lugs 11 in a manner indicated in Fig. 6 of the drawing. The racing plate is then ready for its final formation in one direct coining operation. The coining die is formed with an upper section 39 and a lower section 40 as shown in Fig. 8 of the drawing. The cavity in the die section 40 agrees with the configuration of the finished racing plate and includes the portion shown in Fig. 8 as well as portions not shown by which the racing plate is shaped as shown in Fig. 1 of the drawings.

Here it will be seen that a continuous flat top face 41 is provided and that the bottom face of the racing plate forming the tread of the shoe is formed with the usual nail groove 42, with per-

forations 43 through which nails may pass. As the coining operation takes place the metal 10, which was originally round bar stock, is forced to fill the toe calk shell 12 as indicated in Fig. 8 and the hollow calk shells 13 as indicated in Fig. 9. Thus, the portion 27 of the toe calk shell will fold over and become embedded in the top face 41 of the racing plate. This is also true of the portion 30 of the toe calk. The tangs 38 of the heel calk shells 13 will fold over and be embedded within the top face 41 of the racing plate.

An enlarged fragmentary view of the bottom face of the toe calk in its final form is shown in Fig. 10 of the drawings and an enlarged fragmentary view of the top face of the racing plate and the toe calk shell is shown in Fig. 11 of the drawing.

Here it will be seen that the notch 22 will occur along the transverse center line of the racing plate and in both the top and bottom faces of the plate when in finally pressed form.

This provides a weakened portion at the center of the toe calk shell 12 which makes it possible for the shoe to be "opened up" or "closed" to conform to the hoof contour of different horses. This eliminates the necessity of making a number of sizes of shoes as would be the case if the toe calk shell 12 were rigid and unbendable.

It will thus be seen that by the method here shown it is possible to produce a strong, durable, light-weight racing plate which may be easily adapted for hoofs of various sizes and contour. It will also be noted that the manufacturing operation is rapid and efficient and that the shoe is novel in design and is made by a new and commercially desirable method.

Having thus described my invention, what I claim and desire by Letters Patent is:

1. A method of producing a racing plate which consists in shaping a length of round bar stock of ductile metal to conform to the contour of a hoof and produce a shoe blank, forming a hollow shell-like toe calk of relatively hard metal, said toe calk being substantially V-shaped in cross-section and being arcuate longitudinally, then placing said toe calk shell and said shoe blank within coining molds and thereafter exerting pressure on the same whereby the shell-like calk will be clinched around the shoe blank, and the shoe blank will be shaped to conform to the configuration of a conventional shoe while completely filling the cavity within the calk.

2. A method of making a racing plate which consists in cutting a piece of round bar ductile metal representing the developed length of a horse-shoe, thereafter shaping the same to conform to the contour of a horse's hoof, then upsetting one end of said material to form the foundation for a heel calk, then pressing a heel calk shell from relatively hard sheet material, said shell being designed to fit over the upset portion of the piece of material and having tangs to fold therearound, then pressing a toe calk shell from relatively hard sheet material, the sheet of material being folded upon itself to be substantially V-shape in cross-section and being arcuately curved to conform to the contour of the bar, thereafter fitting the heel and toe calks on the bar and clinching them therearound, then placing the bar with its associated calks between coining dies and pressing the same to give the racing shoe its final shape and to force the metal into the calks while clinching the calks thereon.

3. The method of making a racing plate horse-

shoe which comprises forming a body blank of light ductile metal, of forming a thin hollow calk-shaped shell of wear-resistant metal, and of subjecting the blank with the calk-shaped shell applied thereto to sufficient pressure within a mold having a shoe forming cavity adapted to receive the calk-shaped shell therein to force the ductile metal of the blank into the hollow shell and to embed a marginal edge of the shell flush with the body portion, thereby to form a horseshoe with a calk of ductile metal covered with a thin shell of wear-resistant metal.

4. The method of making a racing plate horseshoe which comprises forming a body blank of light ductile metal, of forming a thin-walled, hollow concave-convex calk-shaped shell of wear-resistant metal, of placing the body blank with the shell placed with its concavity shaped shell toward the body portion in a mold having a cavity therein to receive the calk-shaped shell therein, and of subjecting the blank with the calk-shaped shell thus applied thereto to sufficient pressure within the mold to deform the ductile metal of the blank, forcing a portion thereof into the hollow shell completely to fill the shell and to embed the marginal edges of the shell flush with the body portion, thereby to form a horseshoe with a calk of ductile body metal covered with a thin shell of wear-resistant metal.

5. The method set forth in claim 4 wherein the shell is notched on one marginal edge thereof substantially midway of its length to facilitate bending of the horseshoe on completion thereof.

6. The method of making a racing plate horseshoe which comprises forming a horseshoe body blank with an excess of light ductile metal, of covering a calk forming area of the body blank with a calk-shaped hollow shell of thin, wear-resistant metal having an open side disposed toward the body blank and of subjecting the thus assembled blank and shell to sufficient pressure in a mold to form the horseshoe body and to force body metal into the hollow shell, filling it.

7. The method of making a racing plate horseshoe which comprises forming a horseshoe body blank with an excess of light ductile metal, of

covering a calk forming area of the body blank with a calk-shaped hollow shell of thin, wear-resistant metal having an open side and a marginally extending portion and of subjecting the thus assembled blank and shell to sufficient pressure in a mold to form the horseshoe body and to force body metal into the hollow shell, filling it, and of embedding the marginally extending portion of the shell in the body metal thereby securing the shell against removal from the body portion.

8. The method of making a racing plate horseshoe which comprises forming a horseshoe body blank with an excess of light ductile metal, of covering a calk forming area of the body blank with a partially formed calk-shaped hollow shell of thin, wear-resistant metal having an open side with the open side toward the blank, of subjecting the thus assembled blank and shell to sufficient pressure in a mold to form the horseshoe body thereby forcing body metal into the hollow shell, filling it, and performing a final forming operation on the shell.

CARL J. NARDON.
